UNITED STATES PATENT OFFICE.

DANIEL MOREAU BARRINGER, OF HAVERFORD, PENNSYLVANIA.

GUN-SIGHT.

1,363,553.

Specification of Letters Patent. Patented Dec. 28, 1920.

Application filed June 29, 1918. Serial No. 242,516.

To all whom it may concern:

Be it known that I, DANIEL MOREAU BARRINGER, a citizen of the United States, and a resident of Haverford, in the county of 5 Montgomery and State of Pennsylvania, have invented certain new and useful Improvements in Gun-Sights, whereof the following is a specification, reference being had to the accompanying drawings.

10 Although my invention may be said to relate primarily to sights for rifles or similar small arms, it is also applicable to machine guns and cannon, and it will, therefore, be understood that in using the expression 15 "gun-sights," I do not thereby intend to limit its use to any particular class or size of guns.

It will also be understood that the invention is adapted for use in connection with 20 any desired adjunctive appliances, such as elevating devices and the like, but to avoid complication I have not shown in the drawings, nor shall I describe in the specification, any of these concomitant features.

25 The features of novelty characteristic of my invention reside in the construction of the rear sight of the gun and can be employed in connection with any desired form of front sight.

30 Furthermore, the characteristic principles of the invention lend themselves to embodiment in structures comprising various developments of detail, and in order that the differentiation between several typical embodiments may be more readily appreciated, I have, in the accompanying drawings, represented a device embodying the main characteristics in progressive steps of detailed 35 development.

40 Thus, Figure I, represents in perspective a gun-sight embodying my invention in a very simple form; Fig. I^a, being a view, in rear elevation, of the same embodiment.

45 Figs. II, III, and IV, are perspective views of sights embodying the invention with what may be considered as cumulative developments of details, Figs. II^a, III^a, and IV^a, being corresponding views, in rear elevation, of said respective embodiments.

50 In Figs. III^a, and IV^a, solid black is employed to indicate conventionally the body or main portion of the respective devices, in order to emphasize, by the stippled bands, certain detail features under conditions

characteristic of the use of the sight at 55 night.

Fig. V, is an enlarged representation of the sight shown in Figs. II, and II^a, showing, in connection therewith, a preferred form of front sight, and so represented in 60 fore-shortened perspective as to indicate the preferred relation between the tip of the front sight and the optical center of the rear sight when shooting point-blank.

Fig. VI, is a similar view of the sight, 65 shown in Figs. IV, and IV^a, indicating in a conventional manner similar to that employed in Fig. IV^a, the appearance of both the front and rear sights when the device is used at night.

70 Referring to Figs. I, and I^a, 1, represents the main block, or body of the sight, which is provided with a dove-tailed base 2, adapted to engage in a corresponding seat in the gun barrel, or in an adjunctive device 75 mounted thereon. The rear face 3, of the sight (or that which is toward the observer), is inclined preferably at an angle of 45° to the horizon, such inclined face terminating, across its central region in a horizontal 80 straight edge 4, but being continued upward on each side in two similar vertical projections 5, 5, thus forming a flat bottomed notch accurately defined to the eye as rectangular and symmetrically transverse to 85 the axis of the gun-barrel, when properly viewed from the rear.

A straight groove is formed longitudinally along the center of the inclined face 3, and terminates accurately in the center of 90 the rear edge 4, of the notch, said groove being adapted to receive the strip 6, of material which is relatively bright, as compared with the dark surface of the metal of the body. For permanency, I prefer to make 95 this inlaid strip of ivory or some non-tarnishing metal, but paint, enamel or other adhesive material, contrasting in color with the main surface, might possibly be employed.

100 In Figs. II, and II^a, another embodiment is shown, the sight being similarly constructed with a body 21, dove-tail 22, rear inclined face 23, central notch 24, between the projections 25, 25, and inserted piece 26, of bright material, but with the additional feature that a deep groove 27, of semi-circular cross-section is formed longitudinally

along the center of the notch 24, from front to rear, the upper extremity of the bright piece 26, terminating accurately at the bottom of the groove, as indicated.

5 At the rear extremity, the outline of the edge of the groove 27, is semi-oval, by reason of the angle of intersection of the inclined rear face 23, as indicated at 28. When, however, the sight is viewed from 10 the rear, in the position of use, as shown in Fig. II^a, the true semi-circular cross section of the groove 27, will be apparent.

Referring now to Figs. III, and III^a, a still further development of a typical device embodying the principle of the invention is shown. Save in one particular, about to be referred to, the structure of the sight shown in Figs. III, and III^a, is represented as identical with that shown in 20 Figs. II, and II^a, the several parts being indicated by similar figures raised by 10. Thus, the body of the sight is 31, the dovetail 32, etc.

Here, as in the case shown in Fig. II, the 25 bright strip 36, terminates accurately at the bottom of the semi-cylindrical groove 37, but I form in the inclined face of the sight, a semi-oval shallow groove 39, optically symmetrical with the outline of the rear extremity 38, of the groove 37, but with slight interspace, as shown. Said groove 39, is adapted 30 to retain a band of material which is luminous or visible in the dark. Such material, for instance a phosphorescent paint, can be 35 rubbed into the groove, the surplus being completely wiped away so as to form a clearly defined luminous band, accurately surrounding, and optically corresponding with, the outline of the rear extremity 38, 40 of the groove 37. The bright strip 36, in this instance bisects the luminous groove 39, and need not itself be luminous when the device is used at night. Under these 45 conditions, the appearance of the rear face of the sight, when used in the dark, will be understood by reference to Fig. III^a, where the solid black portion indicates the general rear inclined face of the sight, the stippled portion 39, representing the luminous band, here shown as interrupted at 50 the center of its bottom portion, by the non-luminous strip 36.

Referring now to Figs. IV and IV^a, a still further typical development is shown, 55 in which I have indicated all the structural parts of the sight, with the exception of the feature about to be mentioned, as substantially identical with those shown in Fig. III, the several parts being indicated by similar 60 numerals again raised by 10. Thus, the main body is marked 41, the dovetail 42, etc. In this instance, however, I provide two longitudinal grooves 40, which extend preferably along the entire inclined surface 65 43, near its edges, terminating in accurate

central relation to the two uprights 45. Said grooves 40, are adapted to be filled with material luminous in the dark, in the same manner as is the groove 49, which surrounds the rear extremity of the groove 47, 70 so that, in the dark, the rear of the sight will present the appearance indicated conventionally in Fig. IV^a, where the stippled lines 40, are shown foreshortened and disposed with mathematical accuracy on each 75 side of the central notch 47, and luminous band 49.

Referring now to Fig. V, I have therein shown a preferred form of front sight, in what I consider the most satisfactory elevation relatively to a rear sight, of the character shown in Fig. II. Said front sight comprises a vertical stem 50, surmounted by a bead 51, and, as the result of experience I consider it desirable (though, of course, not 85 essential), that when the observer is aiming point-blank at a given object, the top portion of the periphery 51, should be tangential to the line which the rear edge of the notch 14, presents to the eye. 90

In Fig. VI, I have represented conventionally a preferred embodiment of front sight to be used in connection with the form of rear sight shown in Figs. IV, and IV^a, in this instance I consider it desirable that 95 the stem 60, of the front sight should not be luminous at night, and hence have indicated it by dotted lines, but the tip or bead 61, should have its rear face covered with a luminous material, such as phosphorescent 100 paint, and for the best results, the upper surface of the periphery of the bead 61, should be tangential to the transverse edge line of the notch 34.

Having described these several typical 105 embodiments of my invention, I will now proceed to describe what may be termed the optical characteristics due to the structural arrangement of the parts which embody the new and improved features. 110

A primary and important feature consists in the fact that an elongated sloping surface rising at an angle of approximately 45°, to the horizontal is presented to the eye instead of a vertical surface, as in most rear 115 sights. The result is that if an optically bright line extends along the exact longitudinal center of this surface, the eye will catch this line near its base and follow it up to the bottom of the notch in the upper 120 portion of the sight, without conscious effort. To illustrate the matter by familiar examples, the eye will catch and follow a straight road extending up an evenly inclined hill from its lowest to its highest 125 point, much more readily, and, so to speak, automatically, than it would follow a vertical chimney or tower from its lowest to its highest point. I believe that this phenomenon is due to what may be considered as a 130

part of the general principles, upon which the so-called laws of perspective depend, but this statement, however, is simply by way of explanation and is not intended to be restrictive. Whatever the true explanation, however, the specific effect here referred to is substantially absent if the angle of inclination of the rear face of the sight is greatly below 45° .

10 Another desirable feature is that by the use of this optically bright line, in perspective, I may employ a relatively wide or open notch, with the effect that the user of the sight may readily see all around the object 15 or point at which he is aiming. Of course this advantage of the bright band in connection with the wide notch is most perfectly realized when the notch is wide as compared with the front sight employed,—or, in other 20 words, get a general view of portions of his objective adjacent the point aimed at.

While this feature of a wide notch is not in itself new, its value is greatly enhanced when employed in connection with the inclined rear surface and bright central line 25 thereon. This line produces its effect of causing the eye to locate the front sight in the center of the notch most perfectly when the line is, relatively, quite narrow in comparison with the notch,—irrespective of the 30 relative width of notch and front sight. It may be added that the peculiar value of the combination above described is more notable when the observer is obliged to aim quickly 35 at a moving object, the conditions being quite different from those which exist when aiming at an ordinary stationary target.

All these points are true of the simplest type of my improved sight shown in Figs. 40 I, and I^a , but with the progressive development of details indicated in the remaining figures, still greater accuracy of aim may be obtained almost unconsciously on the part of the observer, by reason of the optical 45 characteristics afforded by the parts. Thus, in the arrangement shown in Fig. II, the bright line 26, terminates accurately at the bottom of the central groove 27, and the eye is not only additionally guided by the 50 two uprights 25, on either side of the wide notch, but also the closer definition afforded by the rear edge of the semi-circular groove 27, to which the inclined bright strip 26, directly leads.

55 Referring now to the types of the invention shown in Figs. III, III^a , and IV, IV^a , the usefulness of the device is enhanced when the device is used in the dark, the eye being guided by the luminous band 60 symmetrically arranged with relation to the line of profile, and, as shown in Fig. VI, the tip or bead of the front sight, being also luminous on its rear face, can readily be found by the observer and located centrally with relation to the straight bands

40, and to the optical center of the curved band 49, which surrounds the rear face of the groove 47, the eye being aided by the interruption of the luminous band 49, at the center of its lowest portions.

70

Having thus described my invention, I wish it to be understood that certain terms are employed in a relative sense and are not to be strictly interpreted. Thus, in speaking of the strip 6, and the corresponding elements in the other figures, I have referred to it as "bright." By this term I do not mean that it should be so brilliant as to dazzle the eye, but merely that it should be distinctively conspicuous by contrast with the general inclined surface of the rear face of the sight, which ordinarily would be of the dull color characteristic of blued steel or gun metal. So also in referring to the luminous bands, I do not mean that they should be of such a degree of luminosity as to disturb the eye, but merely that by contrast with the surrounding surfaces they should be distinctly and clearly marked when viewed in the dark.

90

Furthermore, in employing the terms "strip" and "band," I do not mean that these elements are necessarily continuous lengthwise, since a similar optical effect could obviously be obtained by a device having the desired general line, but non-continuous in actual structure.

95

Finally, I desire to state that in recognizing the state of the prior art, relating to gun-sights I include Letters Patent of the United States No. 494,240, granted to me under date of March 28, 1893, and, of course, desire that the present invention shall be clearly distinguished from anything which is shown or described in said Letters Patent.

105

I claim:—

1. A gun-sight, comprising a body with an extended rear face, inclined away from the eye at angle of about 45° at even the shortest ranges, and terminating at its upper extremity in a wide notch affording the marksman a general view of portions of his objective adjacent the point aimed at, and having two similar vertical projections at its sides; in combination with a bright strip 110 relatively narrow in comparison with the notch extending longitudinally along the central line of the inclined rear face of said body and terminating upwardly, at the rear edge of said notch, symmetrically between the proximate faces of said projections, so as to afford the eye automatic guidance to the center of the notch and facilitate and expedite centering of the point aimed at therein.

115

2. A gun-sight, comprising a body with an extended rear face, terminating at its upper extremity in a notch so wide in comparison with the sight with which it is to be employed as to afford the marksman a gen- 120

125

130

- eral view of portions of his objective adjacent the point aimed at, and having two similar vertical projections at the sides; in combination with a bright strip extending 5 longitudinally along the central line of the inclined rear face of said body and terminating upwardly, at the rear edge of said notch, symmetrically between the proximate faces of said projections, so as to afford the 10 eye automatic guidance to the center of the notch and thus facilitate and expedite centering of the front sight and the point aimed at therein.
3. A gun-sight, comprising a body with 15 an extended inclined rear face, terminating at its upper extremity in a notch having two similar vertical projections at the sides; said notch being provided with a curved groove lying centrally along it from front 20 to rear; in combination with a bright strip extending longitudinally along the central line of the inclined rear face and terminating at the bottom of the edge of said groove, and symmetrically between the proximate 25 faces of said projections.
4. A gun-sight, comprising a body with an extended inclined rear face, terminating at its upper extremity in a notch having two similar vertical projections at the sides, 30 said notch being provided with a curved groove lying centrally along it from front
- to rear; in combination with a bright strip extending longitudinally along the central line of the inclined rear face and terminating at the bottom of the edge of said groove, 35 and symmetrically between the proximate faces of said projections; and a band of luminous material upon said inclined face, in symmetrical relation to the rear edge of said notch. 40
5. A gun-sight, comprising a body with an extended inclined rear face, terminating at its upper extremity in a notch having two similar vertical projections at the sides, said notch being provided with a curved groove 45 lying centrally along it from front to rear; in combination with a bright strip extending longitudinally along the central line of the inclined face and terminating at the bottom of the edge of said groove, and two straight 50 bands of luminous material lying along the inclined rear face, respectively adjacent to the side edges thereof and symmetrical to the center of said notch.

In testimony whereof, I have hereunto 55 signed my name, at Philadelphia, Pennsylvania, this 27th day of June, 1918.

DANIEL MOREAU BARRINGER
